HAT TRIM

This is a division of application Ser. No. 787,690, filed Dec. 30, 1968, titled "Hat Trim Machine," and now U.S. Pat. No. 3,520,261.

BACKGROUND OF INVENTION

This invention relates to a decorative article which may be used for a variety of purposes such as trimming for various fabrics, millinery, or other decorations, and to the manufacture of such articles.

SUMMARY OF INVENTION

It is an object of this invention to provide a decorative trim strip, and, furthermore, to provide simple and effective manufacture of such a strip.

For the achievement of these and other objects, this invention proposes machine stitching a series of purls or loops into a generally resilient elongated strip and imparting a uniform twist to the strip as it leaves the stitching mechanism. More specifically, a decorative yarn is stitched with an elastic pillar such that the yarn projects essentially from one side only of the stitched body including the pillar in the form of purls or loops and is then passed into means for imparting a uniform helical twist to the stitched strip. Preferably, the elastic pillar is in a state of tension as it is stitched with the yarn and will, upon release from stitching mechanism, tend to gather the stitched body of the strip from which the loops project.

The twist imparting means may take the form of a tube having opposite open ends and rotatably mounted at an inclined angle adjacent the stitching mechanism. This tube includes an inner friction surface which engages the strip as it is fed into the tube. Friction between the friction surface and strip, caused by the weight of the strip and the rotation of the tube, imparts a uniform helical twist to the strip.

It is further contemplated that a receiver having at least one open end can be rotatably mounted beneath the lower end of the tube that as the strip exits the lower end of the tube it passes into the rotating receiver. The receiver engages the strip and rotates at a speed approximately equal to that of the tube. The receiver stores the trim strip in a continuous length and, by virtue of its rotation, does so while preventing the disorientation of the uniform helical twist imparted to the strip by the tube.

In the finished strip the purls or loops, although projecting essentially from one side only of the elastic pillar, have the appearance of projecting radially on all sides of an elongated central pillar or, more generally, from the longitudinal axis of the strip. The strip is expandable longitudinally and is resilient so that it will return to a compact helical configuration when any such force is released.

Other objects and advantages will be pointed out in, or be apparent from, the description and claims, as will obvious modifications of the single embodiment shown in the drawings.

DESCRIPTION OF THE DRAWINGS

FIG. 1 is a perspective view showing the apparatus proposed by this invention;

FIG. 2 is a perspective view of the trim strip proposed by this invention showing the article in its

final helical state and also with a portion thereof developed to better illustrate the structural makeup of the strip; and

FIG. 3 is a further illustration of the trim strip showing the stitched body with the interwoven elastic pillar and the loops

DESCRIPTION OF THE PREFERRED EMBODIMENT

10 The article resulting from the practice of this invention will have general application as a decorative trim, but will probably find particular application as a decoration for hats such as knit children's hats.

15 Trim strip 10 proposed by this invention is shown in FIGS. 2 and 3 in somewhat schematic form and is comprised of an elastic pillar 20 and a decorative yarn 22. It will be appreciated that yarn of any variety or color can be used in connection with various types of elastic pillars. As will be described more completely hereinafter, 20 yarn 22 is machine stitched with the elastic pillar 20 by means of a machine 32 which uses a shell or crochet stitch. The stitch is such that a series of purls or loops 25 project from one side of a stitch body 25 which contains pillar 20. This structure is illustrated by portion 26 which has been developed as a straight section for illustrative purposes.

25 Referring now to FIG. 1, trim machine 30 proposed by this invention comprises a combination of a crocheting machine 32 and a twist imparting mechanism 34.

30 The crocheting machine 32 is not shown in detail as the details of the machine are not necessary to an understanding of this invention. It is sufficient to an understanding of the invention to appreciate that two 35 threads such as decorative yarn 22 and elastic pillar 20 are fed to crocheting assembly 33 where they are machine stitched together. The crochet stitch is such that the decorative yarn 22 projects in a series of loops 24 essentially from side of body 25 as shown in FIG. 2 generally at 26. Furthermore, the crocheting machine 32 is effective to stitch pillar 20 into body 25 under tension, or in a stretched condition, so that when the 40 stitched strip is released from the crocheting head the pillar contracts toward its natural condition and gathers body 25. Loops 24 and body 25 are shown to be a uniform straight strip in FIG. 2 at 26 for purposes of illustration; however, in reality, if the stitched strip is left to pass freely and undirected from the crocheting head 45 50 the strip will evolve from the machine in a random, disorganized, twisted shape. This invention is concerned with the problem of preventing this random twist and imparting a desired uniform configuration to the strip to render it more suitable as a trim strip.

55 After the article is processed in the manner proposed by this invention, which will currently be explained, the trim strip 10 of this invention will appear as shown generally at 28 in FIG. 2, that is, as an elongated, expandable, resilient article having permanent uniform helical twist such that loops 24 appear to project radially from the longitudinal axis of the strip as shown in FIG. 2.

60 The machine and method of the proposed invention 65 impart a uniform helical twist to the strip. The elastic pillar 20 in contracting acts to fix the helical twist and thereby results in a strip having the uniform helical configuration.

Structurally, the twist imparting mechanism generally shown at 34 comprises a cylindrical tube 36 having two open ends 38 and 40. Preferably, the inner diameter 42 of the tube is large with respect to the diameter of the trim strip. The tube 36 is mounted on a support base 44 and is supported by rollers 46 and 48 which are disposed on support base 44. In addition to the two rollers 46 on the exposed side of the tube in FIG. 1, two similarly arranged rollers are provided on the opposite side of the tube, one of which is partially visible in the drawing. Rollers 46 and 48 engage diametrically opposite sides of cylinder 36 so that the cylinder is held between the rollers. Rollers 46 are directly connected to base 44 and roller 48 is connected to a support arm 50 attached to support base 44 and extends to the upper side of the cylinder. The tube 36 is rotated by means of a first motor 52 operatively engaged with a pulley 54. Drive belt 56 extends from 15 54 and directly encircles cylinder 36 on its outer surface 60. Preferably belt 56 is disposed in the area of roller 48 which assists in preventing belt 56 from wandering along the outer surface 60 of tube 36 thus preventing any possibility of binding in the system. Also, a circumferential flange 58 is disposed above the 20 lower rollers 46 and is engaged by the rollers to ensure vertical orientation of the tube. Motor 52 is preferably associated with an infinitely variable speed control (not shown) so that the rotational speed of the motor can be precisely varied thereby allowing control of the rotational speed of the tube 36.

The interior of tube 36 is provided with a frictional surface which, as illustrated, comprises friction strips 62 spaced circumferentially along the inner surface 64 of the tube. Friction strips 62 may be any convenient friction material such as felt, the choice determined at least in part by yarn 22. The arrangement of alternate friction strips and open spaces is preferred as it results in periodic engagement of the trim strip by the friction strip with some impact.

Preferably tube 36 is disposed at an inclined angle with respect to crocheting machine 32 such that as the trim is fed into the upper end 38 of tube 36, the weight of trim strip 10 will keep the trim in engagement with the lower portion of inner surface 64 of tube 36 and cause the trim to travel freely through the tube and out of the lower end 40 of the tube.

The weight of the trim strip thus maintains engagement between the strip and tube and due to the frictional engagement between strips 62 and trim strip 10, rotation of tube 36 imparts a uniform helical twist to trim strip 10. More specifically, a helical twist is imparted to the stitched body 25 as it leaves the crocheting assembly 33, the body then carrying the loops in series of uniform convolutions. Thus as the yarn and pillar are stitched together, instead of there being disorganized random twisting of the strip, feeding the trim strip 10 into the rotating tube 36 controls the configuration of the strip 10 into the rotating tube 36 controls the configuration of the strip and a uniform helical twist results. The effect of the helical twist, is to give the trim strip 10 the characteristic or appearance that loops 24 appear to project radially from all sides of the longitudinal axis of the strip as shown in FIG. 2 at 28. Also, the tightness or frequency of the helical twist can be varied by controlling the speed of motor 52. The resulting

strip can be cut into desired lengths and attached, for example, to a child's hat as one or more tassels or braids. The strip 10 has been shown somewhat schematically in FIG. 1 for convenience, the actual structure being more clearly shown in FIGS. 2 and 3.

The trim strip 10 may be cut, either manually or by machine, into desired lengths as it exits the tube 36 to prevent the trim strip from unwinding itself into a random, disoriented configuration. Preferably, tube 36 has a substantial axial length of the trim strip and ensures positive rotation of the trim strip, for example tube 36 should be of a length equal to or greater than the desired length of the particular strip.

As an alternative to cutting the strip at the exit end of the tube, a second cylindrical tube 66 is disposed vertically beneath the lower or exit end 40 of tube 36. Tube 66 has an open end 68 and a closed end 70 such that trim strip 10, as it exits tube 36, can be fed directly into tube 66. Tube 66 is likewise rotatably mounted and is structurally similar to tube 36. Tube 66 is supported on platform 71, which closes end 70 and is capable of rotation about its axis by a motor 72 and carries platform 71 with it.

Cylinder 66 also includes friction strips 76, which are spaced circumferentially along the inner surface of tube 66, and the interaction between friction strips 76 and trim strip 10 is similar to that described with relation to tube 36. Preferably, motor 72 also has infinitely variable speed control which allows control over the rotational speed of tube 66 and it is preferred that tube 66 rotate at approximately the same speed as tube 36. In this fashion, tube 66 acts a storage receiver for trim strip 10 as it is fed through tube 36 and permits manufacture of trim strip 10 in a continuous length with the rotation of tube 66 preventing loss of the helical twist imparted to strip 10 by cylindrical tube 36. The trim strip can later be cut in desired lengths.

The effect of the proposed invention is to provide a new article of manufacture by subjecting two elements to machine stitching and then controlling the manner in which the stitched article leaves the stitching mechanism. The article can be inexpensively mass produced and has an appealing appearance. In addition, due to its expandable, resilient features it can be stretched to separate adjacent convolutions and the adjacent convolutions will snap back to a compact form upon release.

Although the present invention has been disclosed in connection with a particular embodiment thereof, it will be apparent to those skilled in the art that various changes and modifications may be made therein without departing from the spirit of the invention or from the scope of the appended claims.

I claim:

1. An article of manufacture comprising:
an elastic pillar;
an elongated strip of decorative yarn having a stitched body extending the length of said strip and also having a plurality of serially arranged loops projecting from said body,
said elastic pillar interwoven in said body along the length of said body and said strip having a helical twist to form a helix generated along the longitudinal axis of said strip with said body disposed generally centrally of said helix and said serially ar-

ranged loops disposed in convolutions about the axis of said helix,
said strip being flexible and having a normal relaxed position wherein adjacent convolutions of said helix are compactly arranged with said loops projecting radially from all sides of the longitudinal axis of strip and said strip having a generally cylindrical appearance,
and said strip being expandable longitudinally to

separate said adjacent convolutions exposing said helical form and being resiliently urged toward said normal position by said pillar to return to said normal position when the expanding force is released.

- 5 2. The article of claim 1 wherein said elastic pillar tends to hold said stitched body in a gathered condition.
